ABSTRACT OF THE DISCLOSURE

Presoak compositions for cleansing, sanitizing and deodorizing fabrics soiled with a combination of organic and bacterial soils, and particularly diapers, prior to washing are provided. The compositions comprise an organic N-chloro compound which hydrolyzes to yield positive chlorine, a sulfamic acid compound, a polyphosphate, an inorganic buffer salt, sodium tetraborate and an anionic or a nonionic surfactant. The particular advantages of these compositions are in their combination of excellent stability under the adverse presoak conditions which normally cause rapid loss of active chlorine, and their high degree of effectiveness as a presoak agent.

BACKGROUND OF THE INVENTION

Effective cleansing and sanitizing of organically and bacterially soiled fabrics is both necessary and difficult. Diapers are a prime example of this problem. They are worn by infants and young children who are highly susceptible to skin irritation, and therefore when they are soiled these garments must be sanitized as well as cleaned before reuse. The same problem exists with other fabrics which are subjected to organic and bacterial soiling, for example with handkerchiefs, towels, bedding and the like.

It has become fairly general practice for the homemaker to soak such soiled fabrics in sanitizing and cleansing solutions before washing them. This is partly a matter of convenience, but importantly it provides for more effective elimination of stains and odors from the fabric. For example, when soiled diapers, which contain a high level of bacteria as well as of other organic soil and stains, are stored in air or in an aqueous solution not containing an effective sanitizer, the bacteria react with organic matter to evolve noxious ammonia odors. Furthermore, during such storage stains frequently "set" in the diaper and become very difficult to remove upon subsequent washing.

Formulators of products used in presoaking fabrics which are soiled with organic and bacterial matter are fully aware of the special requirements they face. They realize, for example, that not only must the product be capable of removing stubborn stains and odors while overcoming a particularly aggravated sanitizing problem, but that in addition it must be capable of retaining its sanitizing effectiveness over a substantial period of time. They realize also that the user does not want a product which creates odors on its own, or which causes excessive fabric degradation.

These requirements for an effective presoak product obviously are severe, and the trade has devoted much effort to their solution. Compositions have been provided which contain any of a variety of active chlorine, quaternary ammonium or active oxygen sanitizing materials. Examples of active chlorine products which have been used are chloroisocyanurates and chlorinated para-toluene sulfonamide, while perhaps the most widely used active oxygen compound has been sodium perborate. Compositions containing these sanitizing agents have been used as direct cleansing compositions and as presoak products. In the latter case, the soiled fabric is soaked in a solution of the compositions for on the order of 12 to 48 hours, according

2

to individual preference, prior to being washed with ordinary cleansing solutions.

While these prior art compositions generally have done an acceptable job, however, none of them has provided all of the desired characteristics of effective cleansing, destaining, sanitizing, odor removal and residual odor control during extended presoak periods. Accordingly, work has continued toward provision of more effective presoak compositions for soiled fabrics.

SUMMARY OF THE INVENTION

We have now found that fabrics soiled with organic and bacterial matter can be cleansed, sanitized and deodorized very effectively during presoaking with certain new compositions which are stable in use and which do not form odors or damage fabrics. Our new compositions contain as essential ingredients an N-chloro compound which hydrolyzes to yield positive chlorine ions, and preferably a chloroisocyanuric compound in an amount to provide in aqueous solution about 50 to 250 p.p.m. of available chlorine, sulfamic acid in an amount to provide an NH to Cl⁺ ratio in solution of about 0.5 to 5:1, and preferably of 1 to 1, 20 to 50%, and preferably 25 to 35%, by weight of a polyphosphate, preferably sodium tripolyphosphate, potassium tripolyphosphate, sodium pyrophosphate or potassium pyrophosphate, 20 to 40%, and preferably 25 to 35%, by weight of sodium tetraborate having an Na₂O to B₂O₃ ratio of about 1 to 2.5 and having 1 to 5 moles of water of hydration, 0 to 40%, and preferably 25 to 35%, by weight of an inorganic buffer salt, preferably an alkali metal bisulfate, and about 2.5 to 10% by weight of an anionic or nonionic surfactant.

These compositions are particularly effective when used in a presoak solution in which the soiled fabric article, preferably but not necessarily after a simple rinse in cold water, is soaked at room temperature in the solution for about 12 to 48 hours before being washed in any useful soap or detergent washing solution. Alternatively, the compositions may be used in ordinary washing cycles, for example in a home automatic clothes washer, in commercial laundry equipment or by hand. These compositions are particularly effective when used at ambient temperature, although they are effective at a temperature as high as 140° F.

DESCRIPTION OF THE INVENTION AND THE PREFERRED EMBODIMENTS

The organic N-chloro compound is included in our compositions as a source of available chlorine, which preferably should be present in the amount of about 100 to 120 parts per million (p.p.m.) in the sanitizer bath for best germicidal effectiveness. Obviously it is possible to depart from this available chlorine level to a reasonable extent while still providing satisfactory sanitization, and in this connection often the bath may contain about 50 to 250 p.p.m. of available chlorine. However, in the event too little available chlorine (less than about 50 p.p.m.) is employed insufficient sanitizing occurs, while if too much available chlorine (above about 250 p.p.m.) is present, chlorine odor may become a problem both in the bath and on the rinsed product. Generally speaking the N-chloro compound when employed in the amount of about 1 to 15% by weight, depending on the available chlorine content of the particular compound, in our compositions provides the desired amount of available chlorine in the sanitizer bath.

The chloroisocyanurates, including the sodium and potassium dichloroisocyanurates as well as trichlorocyanuric acid and complexes of potassium dichloroisocyanurate and trichloroisocyanuric acid, are the preferred N-chloro compounds for use in our compositions. The preferred complex is that which is composed of 4 moles of the potassium

salt and 1 mole of the trichloroisocyanuric acid. The chloroisocyanurates generally may be used, provided they are stable and sufficiently soluble in water to dissolve at the levels used. Other useful N-chloro compounds include 1, 3-dichloro - 5,5 - dimethylhydantoin, N-monochloro-C,C-dimethylhydantoin, methylene-bis-(N-chloro-C,C-dimethylhydantoin), 1,3 - dichloro - 5-methyl-5-isobutylhydantoin, 1,3 - dichloro - 5 - methyl-5-ethylhydantoin, 1,3-dichloro-5,5 - diisobutylhydantoin, 1,3-dichloro-5-methyl-5-n-amylhydantoin, sodium p-toluene sulfonchloramide,

The sulfamic acid is employed in sufficient quantity to provide an NH to Cl⁺ ratio of about 0.5 to 5.0:1, and preferably of 1:1 in a presoak solution. It may be introduced as such or as a water-soluble N-alkyl sulfamic acid derivative such as N-methyl sulfamic acid or N-ethyl sulfamic acid. The alkyl groups in the useful N-alkyl sulfamic acid derivatives have 1 to 4 carbon atoms; only one such group should be present on the molecule. Use of an excess of sulfamic acid will not deleteriously affect the useful properties of the presoak composition.

The sulfamic acid functions as a stabilizer in cooperation with the other ingredients of our composition to limit undesirable chlorine odor and chlorine decomposition, and thereby permits retention of sufficient chlorine during the presoak period to provide proper sanitizing. It is significant that available chlorine stabilizers used in other kinds of compositions, for example, urea or urea derivatives such as 1,3-dimethyl urea, are not effective in providing proper stabilization against undue loss of available chlorine in the presence of organic and bacterial soils such as encountered in soiled diapers. It is quite surprising that our sulfamic acid has the required stabilizing effectiveness, when it is realized that presoak solution used to treat soiled diapers come into prolonged contact with a number of chemicals which normally destroy the effectiveness of germicidally active sanitizers.

The alkali metal polyphosphates are employed in our compositions as builders which enhance their detergency and cleansing effect. They are generally employed in the amount of 20 to 50%, and preferably 25 to 35%, by weight of the composition, although slightly more or less of this ingredient may be utilized without serious disadvantage. Useful polyphosphates include the sodium and potassium tripolyphosphates and the sodium and potassium pyrophosphates, as well as other alkali metal polyphosphate detergent builders.

The sodium tetraborate employed in our composition is a material having an Na₂O to B₂O₃ ratio of about 1:2.25, and which contains 1 to 5 moles of hydrated water. It is employed in the amount of about 20 to 40%, and preferably 25 to 35%, by weight of the composition. The tetraborate, in cooperation with the other ingredients of our composition, is effective in improving rinsability or draining.

The inorganic buffer salts, that is salts of strong inorganic acids which have an acid reaction in aqueous solution, employed in our compositions include the alkali metal bisulfates, preferably sodium bisulfate or potassium bisulfate, sodium acid pyrophosphate, monosodium phosphate, or combinations of such buffer salts. These materials provide pH control in the composition, and generally are employed in the amount of 0 to 40%, and preferably 25 to 35%, by weight of the composition. These materials are useful in that our compositions, which employ sulfamic acid together with a chlorine compound, should have an essentially neutral pH (between about 6.0 and 7.5) for maximum chlorine solution stability. Even absent a buffer salt, however, our compositions have reasonable and useful stabilities under presoak conditions.

A low-foaming anionic or nonionic surfactant is employed in our composition in the amount of 2.5 to 10% by weight. Preferably 5% by weight is used in the case of the anionic surfactant, while 7.5% by weight is preferred when a nonionic surfactant is employed.

Anionic surfactants are preferred. Their use in combination with borates provides especially good rinsability of soaked and washed diapers and improves the sanitizing action of chlorine. Nonionic surfactants also give satisfactory performance in our compositions, however.

Anionic surface active agents useful herein are non-soap synthetic detergents, including those which are made up of water-soluble salts and organic sulfuric reaction products having from about 8 to 18 carbon atoms in the form of an alkyl radical within the molecular structure and containing sulfuric or sulfonic acid ester radicals. Typical examples of these anionic surface active agents are sodium or potassium alkyl benzene sulfonates in which the alkyl group contains from about 8 to 18 carbon atoms, e.g., sodium dodecyl benzene sulfonate and sodium tri-decyl benzene sulfonate; the sodium and potassium alkyl glycerol ether sulfonates, including esters of high fatty alcohols derived from the reduction of coconut oils; the reaction products of higher fatty acids, e.g., coconut oil with sodium or potassium isethionate; sodium or potassium alkyl sulfonates and sulfates obtained by sulfonation of coconut or tallow fatty alcohols and mixtures of such alkyl sulfates; dialkyl esters of sodium or potassium salts of sulfosuccinic acid; sodium and potassium salts of sulfated or sulfonated monoglycerides, e.g., those derived from coconut oil; sodium or potassium salts of higher fatty alcohol esters of sulfocarboxylic acids, e.g., sodium salt of lauryl alcohol ester of sulfoacetic acid; and other anionic agents set forth in U.S. Pat. 2,486,921 issued to Byerly on Nov. 1, 1949. If desired, the anionic surfactant can be added in the form of a dense, dry bead or as a flake admixed with sodium sulfate.

Examples of other useful anionic non-soap synthetic detergents are acyl sarcosinates, e.g., sodium N-lauroyl sarcosinate. The sodium alkyl benzene sulfonates in which the alkyl group contains about 9 to about 15 carbon atoms are preferred in the practice of this invention.

Nonionic surface active agents useful in the present invention are non-soap synthetic detergents including those made up of a water-solubilizing polyoxyethylene group in chemical combination with an organic hydrophobic compound. Among the hydrophobic compounds which can be used are polyoxypropylene, the reaction product of propylene oxide and ethylene diamine, aliphatic alcohols, etc. Examples of nonionic synthetic detergents useful in the present invention are, condensation products of 6 to 30 moles of ethylene oxide, and preferably 7 to 11 moles, with 1 mole of an alkyl phenol containing 6 to 12 carbon atoms in the alkyl group; condensation products of 6 to 30 moles of ethylene oxide with 1 mole of an aliphatic straight or branched chain alcohol containing 8 to 18 carbon atoms; condensation product of ethylene oxide and the reaction product of propylene oxide and ethylene diamine; nonyl phenol polyethoxy ethanol (commercially known as "Triton N" series); isoctyl phenol polyethoxy ethanol (commercially known as "Triton X" series).

Another well known group of nonionic detergents is known under the trade name of the "Pluronic" series. These compounds are the reaction products obtained by condensing ethylene oxide with a hydrophobic base produced by the condensation of propylene oxide with propylene glycol, and having molecular weights on the order of about 1800. The addition of polyoxyethylene radicals to the hydrophobic base, increases the water solubility of the nonionic detergent and concurrently increases the foaming properties of the detergent in aqueous solution in proportion to the mole ratio of polyoxyethylene radicals to the hydrophobic base. In general, a surfactant which has a mole ratio of 7.5 moles of ethylene oxide per mole of an alkyl phenol, e.g., nonyl phenol, is low-foaming while one with a mole ratio of 10:1 foams moderately. The molecular weight of these nonionic synthetic detergents will range from as low as 800 up to about 11,000.

Nonionic surfactants which meet these requirements also include the low alkyl ethers of polyoxyethylated

octylphenols such as those sold under the Triton CF trade name, for example "Triton CF-54" which is the butyl ether of polyoxyethylated octylphenol; an alkyl ether of polyoxyethylated alkanol such as "Surfactant DF-12," polyoxyalkylene glycols having a plurality of alternating hydrophobic and hydrophilic polyoxyalkylene chains, the hydrophilic chains consisting of linked oxyethylene radicals and the hydrophobic chains consisting of linked oxypropylene radicals, said product having three hydrophobic chains linked by two hydrophilic chains, the central hydrophobic chain constituting 30% to 34% by weight of the product, the terminal hydrophobic chains together constituting 31% to 39% by weight of the product, the linking hydrophilic chains together constituting 31% to 35% by weight of the product, the intrinsic viscosity of the product being from about 0.06 to 0.09 and the molecular weight of the product being from about 3000 to 5000, all as described in U.S. Pat. 3,048,548; the alkyl polyoxyalkylene ether alcohols based on straight chain biodegradable hydrophobic segments, for example "Trelolite H-0307-S" and, the water soluble benzyl ether of octylphenol condensed with ethylene oxide. Other nonionic surfactants are suitable for use in the herein preparations and it is not intended to exclude any surfactant possessing the above properties.

The nonionic surfactants particularly useful in the herein compositions are the nonionic surfactants resisted to the action of available chlorine, especially those having the following formula:

in which R is an alkaryl group in which the alkyl group has 6 to 13 carbon atoms or an alkyl group having 8 to 18 carbon atoms, x is 10 to 18, and R' is an alkyl, aryl, alkaryl or aralkyl group having 3 to 12 carbon atoms. The preferred agents are those in which R is an alkyl phenylene group in which the alkyl group has 8 to 9 carbon atoms, x is 10 to 18 and R' is an alkyl group having 3 to 7 carbon atoms or is a benzyl group.

The compositions of our invention generally are used in the amount of about $\frac{1}{4}$ to $\frac{1}{4}$ ounces per gallon (1.87 to 9.37 grams per liter) of water, and preferably $\frac{1}{2}$ ounce per gallon (3.75 grams per liter) of water, and when so used provide a sanitizing bath containing on the order of 50 to 250 p.p.m., and preferably 100 to 120 p.p.m., of available chlorine.

Our compositions are useful in presoaking and sanitizing soiled fabrics by any of a variety of means. Preferably, but not necessarily, before being subjected to a solution of our compositions the soiled fabric is rinsed to remove excess solids and soiling liquids, normally at ambient temperatures. The soiled fabric, either with or without such a rinse, is soaked before being washed in a

solution of our composition containing about 50 to 200 p.p.m. of available chlorine for any desired presoak period, usually about 12 to 48 hours, following which it is washed with an ordinary soap or detergent solution. The stability of our compositions is such that the solution does not lose sufficient available chlorine to become ineffective, despite the aggravated conditions of such a soak.

Alternatively, the soiled fabric with or without a presoak may be washed in an ordinary washing cycle in a solution of our composition containing about 50 to 250 p.p.m. of available chlorine, employing either a hand wash, an automatic home washer or commercial laundry equipment. These solutions may be used at ambient temperatures, although such operations are usually conducted at about 120 to 140° F. in washing cycles.

The ingredients of our compositions are blended in any equipment which provides mixing, for example in a paddle mixer, a Hobart mixer, a Patterson-Kelly Twin Shell blender, or the like, to provide a uniform and homogenous composition. Preferably the polyphosphate and sulfamic acid are blended together, followed by the tetraborate, buffer salt and surfactant in that order with the N-chloro compound being added last. In the case of liquid surfactants, these surfactants should be taken up on the polyphosphate and tetraborate prior to addition of the remaining components as given above.

Our compositions are highly stable in storage, although of course when they are exposed to excessive amounts of moisture the N-chloro compound reacts to release available chlorine. Accordingly, it is desirable to store them in containers which have some provision for keeping out excessive moisture, for example in pasteboard cartons with a moisture barrier wrapping or in fiber drums with polyethylene or other water-proof liners.

The following examples are given by way of illustration of this invention only, and are not to be considered as limiting the scope thereof in any way. The compositions of these examples were prepared by blending the ingredients in a paddle mixer in the order given above until uniform, homogeneous compositions resulted.

The compositions of Examples 1 and 2 in Table I were evaluated for performance as presoaks for soiled diapers. In a general test, these two compositions were dissolved in water ($\frac{1}{2}$ ounce per gallon), and soiled cotton diapers were soaked in the solution for 24 hours. They were then washed in a standard detergent wash. The presoak eliminated odors and stains and prepared the diapers well for washing.

Diaper damage was also found to be negligible. In that test, after 24 and 48 hour soaks of clean cotton diapers in aqueous solution of the composition of Examples 1 and 2 ($\frac{1}{2}$ ounce per gallon in each case), the fabrics showed only slight fluidity increases. The test was run in accordance with AATCC Method 82—1961 and fluidity increases of only 1 Rhes units (24-hour soaked diaper) and 2 Rhes units (48-hour soaked diaper) were measured. These values are consistent with acceptable practice.

Representative compositions of Examples 1 and 2 (see Table I), as well as of Comparative Examples A-E (see Table II) were also tested for specific properties on soiled cotton diapers as recorded below.

Chlorine stability in solution

The percentage loss of available chlorine from solutions of representative compositions, after 24 and 48 hours during which the solutions were used as presoak baths for diapers in either unsoiled, rinsed soiled or unrinsed soiled condition, were obtained. The tests were carried out at 70° F. Results are given in Table III which follows; this series of experiments demonstrates the effect of not employing a sulfamic acid compound as a stabilizer in the system.

TABLE III.—CHLORINE SOLUTIONSTABILITY
(Expressed as percent loss of initial available chlorine)

Home use performance

In a home use test, the compositions of various of the examples were performance-tested on naturally-soiled cotton diapers which had been worn by a young infant. Presoak solutions containing $\frac{1}{2}$ ounce per gallon of the compositions of Examples I and A were used while 3 tablespoons per gallon of the Example C solution was used and $1\frac{1}{4}$ tablespoons per gallon of the composition of Example D was employed. The amounts for Examples C and D were taken from manufacturer's literature. Soiled diapers from which excess solids had been removed, were tested either as is or after being rinsed, as noted. The results of the tests are shown in Table IV which follows. This demonstrates that the compositions of Examples 1 and 2 of this invention provide an excellent presoak result, whereas the compositions of Comparative Examples A, C and D were deficient in one or another characteristics.

TABLE IV.—HOME-USE PERFORMANCE

Diaper pretreatment	Example	Odor formation				Diaper appearance	
		Initially	24-hr. soak	48-hr. soak	24-hr. soak	48-hr. soak	
Treated both as is and after a pre-rinse.	1	None-----	None-----	None-----	Slight stains, no discoloration.	Slight stains, no discoloration.

Do-----	E	-----	-----	-----	-----	-----	

Dry storage stability

The composition of Examples 1 and B, the latter being a comparative example, were tested for dry storage stability. The results, given as percent loss of initial avail-

able chlorine after two weeks permeable¹ and four weeks sealed² storage are given in Table V which follows. These tests demonstrate the decomposing effect of a sodium tetraborate having 10 molecules of water of hydration as compared with a sodium tetraborate having 5 or less molecules of water of hydration. These test methods are accelerated tests; the values shown for Example B correlate well with commercially unacceptable storage stabilities, whereas the values for Example 1 correlate with commercially acceptable stabilities.

TABLE V.—DRY STORAGE STABILITY

Example	Percent loss of initially available chlorine	
	Two weeks permeable ^a	Four weeks sealed ^b
I-----	20	0
B-----	83	68

^a Samples in appropriate containers are capped with a piece of 2 mil polyethylene/paper laminate (moisture permeable), sealed with plastic tape, and stored in a controlled oven at $100 \pm 2^\circ$ F. and $80 \pm 5\%$ relative humidity.

^b Samples in appropriate containers are stoppered with rubber stoppers, sealed with plastic tape and stored in an oven as described in (1).

Germicidal effectiveness

The composition of Example 2 (this invention), was tested for germicidal effectiveness against a sodium hypochlorite control. The results of 24-hour contact time tests employing selected bacteria commonly found in diapers soiled by infants and each of a sodium hypochlorite control and the diaper presoak solution of Example 1, are given. The tests were run employing undiluted and 1:10 Eugon Broth (organic nutrient broth) solutions to simulate heavy organic soil load on germicidal agents.

TABLE VI.—GERMICIDAL EFFECTIVENESS

Example	Test medium ¹	P.p.m. of NaOCl at pH 8.5 to which 100 p.p.m. available chlorine from example is germicidally equivalent after 24 hour contact time		
		<i>E. coli</i>	<i>S. aureus</i>	Lactobacillus
2-----	{ Undiluted broth----- Diluted broth 1:10-----	100 100	100 100	$>10^0$
2-----	1	100	100	$>10^0$

¹ The test media was an organic nutrient broth (Eugon Broth) used to present a controlled source of organic soil to the germicides, this simulating the organic soil found in naturally soiled diapers.

The above examples, including the comparative examples, demonstrate the effectiveness of the compositions of this invention as cleansing, sanitizing and deodorizing agents for presoaking and washing soiled fabrics. The examples demonstrate the effectiveness of the compositions in treatment of especially difficult articles, namely, soiled cotton diapers. They are equally useful with other cellulose and synthetic fabrics, and with such fabrics soiled with other combined organic-bacterial matter.

The desirable properties of these compositions are achieved through the coaction of the various ingredients which have not heretofore been incorporated together into presoak compositions. Obviously, the above examples can

be multiplied to show the effectiveness of a variety of compositions within the scope of this invention.

What is claimed is:

1. A composition for cleansing, sanitizing and deodorizing fabrics soiled with organic and bacterial matter, consisting essentially of an organic N-chloro compound which hydrolyzes to yield positive chlorine ions in an amount to provide in aqueous solution 50 to 250 parts per million of available chlorine, sulfamic acid in an amount to provide an NH to Cl⁺ ratio in solution of about 0.5 to 5:1, 20 to 50% by weight of an alkali metal polyphosphate, 20 to 40% by weight of sodium tetraborate having an Na₂O to B₂O₃ of about 1 to 2.5 and having 1 to 5 moles of water of hydration, 0 to 40% by weight of an inorganic buffer salt of a strong inorganic acid, said salt having an acid reaction in aqueous solution, and 2.5 to 10% by weight of an anionic or a nonionic water-soluble surfactant.

2. The composition of claim 1 in which the N-chloro compound is present in an amount to provide in aqueous solution 100 to 120 parts per million of available chlorine, the sulfamic acid is present in an amount to provide an NH to Cl⁺ ratio in solution of 1:1, the polyphosphate is present in an amount of 25 to 35% by weight, the sodium tetraborate is present in an amount of 25 to 35% by weight, and the inorganic buffer salt is present in an amount of 25 to 35% by weight.

3. The composition of claim 1 in which the N-chloro compound is a chloroisocyanuric compound.

4. The composition of claim 1 in which the N-chloro compound is sodium dichloroisocyanurate and the polyphosphate is sodium tripolyphosphate.

5. The composition of claim 1 in which the surfactant is an anionic surfactant.

6. The composition of claim 1 in which the N-chloro compound is sodium dichloroisocyanurate, the polyphosphate is sodium tripolyphosphate and the surfactant is an anionic surfactant.
